UNITED STATES PATENT OFFICE

VIRGIL W. BLANCHARD AND VIRGIL W. BLANCHARD, GUARDIAN OF LUTHER S. BLANCHARD, (AN INSANE PERSON,) OF NEW YORK, N. Y.

HYDROCARBON-BURNER.

No. 890,652.

Specification of Letters Patent.

Patented Oct. 6, 1908.

Application filed January 22, 1906. Serial No. 297,249.

To all whom it may concern:

Be it known that we, VIRGIL W. BLANCHARD, *pro se*, of New York, New York county, State of New York, and V. W. BLANCHARD, 5 as guardian of LUTHER S. BLANCHARD, insane, of Weybridge, Addison county, Vermont, have invented certain new and useful Improvements in Hydrocarbon-Burners; and we hereby declare that the following is a full, 10 clear, and exact description thereof, reference being had to the accompanying drawings, which form part of this specification.

This invention is an improvement in an apparatus for burning gaseous fuel particularly designed for use in connection with the 15 heating furnace shown in our application filed January 22, 1906, Serial No. 297,245. It may also be utilized in connection with other furnaces to introduce into the combustion 20 chambers thereof combustible mixtures of vaporized hydro-carbon and water.

The present invention is a novel retort-vaporizer for hydro-carbons, such as kerosene, and also for water; and its object is to 25 enable such hydro-carbons to be vaporized and mixed with suitable quantities of steam produced by vaporizing water, and the products or combustible mixtures of gases thus obtained are discharged from the vaporizer 30 into the burner or combustion chambers of the furnace and augment combustion therein; and when applied to a gas burning furnace materially lessen the amount of gas ordinarily required to produce a given amount of 35 heat, and as the oil is cheaper than the gas, the use of this vaporizer will result in a great saving in the use of the apparatus.

In the drawings, Figure 1 is a vertical central section through the complete apparatus. 40 Fig. 2 is a detail section.

In the drawings B, B are primary mixing tubes through which air and gas are admitted into secondary mixing tubes D suitably supported upon a base A. Above said 45 mixing tubes D is a burner F which is preferably constructed as described in our application above referred to and is hung within a cylinder which is surrounded by flues for air and gases substantially as described in our 50 said application.

Interposed between the lower receiving end of the burner F and the discharge ends of the tubes D is the vaporizer which forms the subject of the present application. This

vaporizer comprises a hollow body which has 55 an upper portion C preferably approximately globular in shape, and a lower skirt portion or hood C', into which the tubes D discharge the upwardly flowing currents of gases. Arranged within the upper portion C of the 60 vaporizer is a hollow retort c, which is open at top and bottom, but is provided internally with an annular flange c' which is preferably inclined to the axis of the retort. This retort is connected to the body C and supported in position therein by tubular arms C² and C³, and in practice we purpose to 65 cast the entire vaporizer and retort in one piece.

The vaporizer is provided below the retort 70 with apertures c³ in its walls for the admission of air into the upwardly flowing current of gases. The hollow arms C² and C³ are respectively connected to pipes E and E' provided with valves e and e', and which are to 75 be connected to reservoirs, or suitable supply of hydro-carbon, such as kerosene, and water.

The vaporizer can be supported in position 80 above the tubes by means of lateral arms C⁴ attached by bolts c⁴ to a plate H supported to the upper end of a cylinder H' surrounding the tubes D and resting on base A.

The upper portion of the retort is inclosed 85 in the air chamber I formed in the casing below the burner and flues. Preferably arranged between the vaporizer and burner is an air heating and supplying device comprising a short pipe or collar J through which the gases rising from the vaporizer pass to 90 the burner F, and projecting into said pipe J are a series of air jet pipes j which receive air from chamber I and discharge it into the upwardly flowing current of gas.

Operation. Combustible mixtures of gas 95 and air are supplied to the vaporizer, through tubes B and D, and flow upward therethrough and through pipe J to the burner F. After the gases are ignited the vaporizer pipe and burner become intensely 100 heated, and then small quantities of oil and water are admitted into the retort c through the pipes E and E'. The oil and water entering the retort are trapped therein by the flange c'; the water entering below the oil, 105 and owing to the heat of the retort are vaporized and converted into hydro-carbon gases and steam the latter slightly below the

former, which issues from the retort and commingle with the upwardly flowing current of gases and air surrounding the retort and are consumed therewith in the burner, 5 increasing the intensity of combustion therein. Air is admitted to the vaporizer both under the hood C' and through the perforations c', and the division of the gases in the vaporizer caused by the retort insure thorough commingling of the gases, vapors and air.

It will be observed that the retort is entirely enveloped by the upwardly flowing current of gases so that the vapors generated 15 in the retort are intimately mixed with gas before they reach the burner. These gases are further supplied with heated jets of air introduced thereto through the jet pipes j as they enter the burner.

20 By the means described we are able to supply the current of gases with vaporized hydrocarbon and with the fuel elements of the water in the most advantageous manner, and the amount of oil and water supplied to 25 the retort is controllable with nicety by means of the valves.

After the parts of the apparatus become thoroughly heated the supply of gas through the tubes D can be reduced until merely 30 enough gas to maintain the retort at a vaporizing temperature is supplied, the vaporized oil and water supplying sufficient gaseous elements to maintain the necessary supply of combustible elements to produce the 35 requisite degree of combustion and heat in the burner.

Obviously this vaporizer could be usefully applied to other forms of heating apparatus, and therefore we do not restrict ourselves to 40 its use in connection with the particular form of apparatus illustrated in the drawing.

Having thus described our invention what we therefore claim as new and desire to secure by Letters Patent thereon is:

45 1. The combination of a mixing tube, a burner above the mixing tube, and a vaporizer interposed between the mixing tube and burner comprising a tubular body through which the current of gases is passed, a retort 50 arranged within the tubular body so as to be enveloped by the upwardly flowing of gas, and means for admitting oil and water into said retort; with a tube interposed between the retort and burner and provided with 55 inwardly and upwardly directed jet pipes for

supplying air to the upwardly flowing gases and vapors.

2. A retort comprising a hollow tubular body provided with a skirt flange on its lower end and air inlet perforations, means for discharging burning gases into said body a tubular retort arranged axially in said body above the perforations and provided with an internal liquid holding flange and adapted to be traversed internally and surrounded externally by the hot gases, hollow arms connecting said retort with the walls of the vaporizer, and oil and water supply pipes connected with said arms. 60 65

3. The combination of a gas and air mixing 70 tube and a burner above the mixing tube; with a tubular fuel vaporizer interposed between but separated from both the burner and mixing tube, and through which the current of gases passes from the tube to the 75 burner; with an air heating device also interposed between the vaporizer and the burner and adapted to be traversed by the gases issuing from the mixing tube and discharge jets of air into the gases. 80

4. The combination of a gas and air mixing tube, a burner above the mixing tube, and a tubular fuel vaporizer interposed between the burner and mixing tube and through which the current of gases is passed 85 from the tube to the burner; with an air heating device interposed between the vaporizer and the burner and traversed by the gases and provided with interior upwardly directed jet pipes adapted to discharge jets of air into 90 the current of gases.

5. The combination of a mixing tube, a burner above the mixing tube, and a vaporizer interposed between the mixing tube and burner comprising a tubular body through 95 which the current of gases is passed, a tubular retort arranged within the tubular body so as to be traversed internally and enveloped externally by the upwardly flowing gases, and means for admitting oil and water into said 100 retort.

In testimony that we claim the foregoing as our own, we affix our signatures in presence of two witnesses.

VIRGIL W. BLANCHARD,

VIRGIL W. BLANCHARD,

Guardian of Luther S. Blanchard.
